AUTOMATIC FADE SIGNAL FOR MOTION-PICTURE REELS

Application filed October 3, 1929. Serial No. 397,096.

The object of the invention is to provide a means for incorporation in the reel structure of motion picture machines to give a continuous audible signal to the operator indicating the approaching end of the film, so that he may be prepared to avoid what is conventionally known as a white screen; to provide a device of this character which may be set to operate with varying numbers of convolutions or turns of films on the reel, so that actuation may be had when there is comparatively few turns left, or a greater number of turns, if occasion demands, as where an operator may have duties taking him away from the machine and would desire a signal at an earlier time than would otherwise be required; and to provide a signalling apparatus of the type indicated which is of simple form and therefore susceptible of cheap manufacture and low marketing cost.

With this object in view the invention consists in a construction and combination of parts of which a preferred embodiment is illustrated in the accompanying drawings, wherein:

Figure 1 is a side elevational view, showing a motion picture reel equipped with the invention.

Figure 2 is an edge view.

Figure 3 is a sectional view on the line indicated by 3—3 of Figure 2.

Figure 4 is a sectional view similar to Figure 3 but showing the released position of the parts.

Figure 5 is a detail view, partly in section and partly in elevation, of the signal actuating means.

The apparatus is housed within the core 10 of the reel with the exception of the tongue 11 which is exterior to the core and adapted for insertion between adjacent convolutions of films. The tongue when engaged between the convolutions of a film holds retracted the cross-head 12 which is carried by a slide 14, the latter being movable longitudinally of a guide 15 which is disposed radially of the reel. The cross-head is drawn normally inwardly by means

of tension springs 16 terminally secured to it and anchored at points in the core.

Movement of the cross-head in its slide effects movement of the clapper bar 17, the latter being designed for rotary movement during which its pawls 18 are impacted with the signal gong 19, the pawls being pivotally mounted on the clapper bar by means of screws 20. The pawls are of tapering form and the pivot screws 20 pass through them at the ends remote from the pointed terminals, so that in the rotation of the clapper bar, the pawls swing outwardly from the axis of rotation thereof and in position to contact with the periphery of the bell or gong 19.

The sliding or longitudinal movement of the slide 14 on which the cross-head 12 is carried is translated into rotary movement to effect actuation of the clapper bar and to this end there is provided a rack bar 21 which is connected with the cross-head by means of the screw 23 and its teeth meshing with the teeth of a pinion 24 of a speed multiplying gearing 25, the terminal gear 26 of which meshes with a pinion 27 carried on the shaft 28 to which the clapper bar is secured.

The slide 14 moves toward and away from the hub 28 of the reel and when positioned remote from the hub, the springs 16 are extended. The tongue 11, when engaged between the convolutions of film holds the slide in its outward position and when the tongue is released, the springs are free to act, drawing the slide and cross-head inwardly and thereby effecting longitudinal movement of the rack bar with the consequent actuation of the speed multiplying gear and the clapper bar, the latter by successive impacts of the pawls on the gong sounding a continuous signal.

Since the tongue, when released by the film must assume a position out of obstructing relation with the latter, it has a hinge connection 29 with the slide which permits it to swing outwardly when released and to enter the guide. A spring 30 secured to the inner periphery of the rim of the core 10 bears laterally against the slide when posi-

tioned away from the hub 28' and is brought into bearing engagement with the tongue when the latter enters the guide, keeping the tongue well outwardly so that it may not engage with the edge of the film as the final convolutions are unwound.

When the film is placed on the reel, the first few convolutions are laid with the tongue free, then the slide is drawn radially outwards and the tongue folded down, after which the laying of the film is continued until completed. When the tongue is thus engaged, the slide and cross-head are in positions to be actuated by the springs, and the signal thereby sounded, when the tongue is released.

To provide for radially drawing the slide outwardly, to permit ready setting of the tongue, a finger knob 31 is employed, this being secured to the slide 14 by means of a stem 32 passing through a slot 33 formed in one wall of the core.

By reason of the slide being mounted in a guide and the tongue having a hinge connection with the former, the springs 16 may be made relatively strong without likelihood of damage to the film at the instant of release of the tongue, since the guide ensures the slide moving always in a plane at right angles to and adjacent the edge of the film. Thus the fulcrum point of the tongue, at the moment of release, is positioned where no great force may be applied to it tending to tear the film, while the potential energy of the springs is sufficient to effect the operation of the speed multiplying gearing to effect a continuous sounding of the gong.

The invention having been described what is claimed as new and useful is:

1. In combination with a motion picture reel having a hollow core, an audible signal mounted in said core, means for effecting a continuous sounding of the signal, a spring actuated slide comprised in said sounding means, and a tongue for insertion between adjacent convolutions of film, said tongue having a hinge connection with said slide.

2. In combination with a motion picture reel having a hollow core, an audible signal mounted in said core, means for effecting a continuous sounding of the signal, a spring actuated slide comprised in said sounding means, and a tongue for insertion between adjacent convolutions of film, said tongue having a hinge connection with said slide, the slide having a finger knob to effect its movement manually in opposition to said spring.

3. In combination with a motion picture reel having a hollow core, a gong mounted within the core, a rotary clapper mounted for impact with the gong, means for actuating the clapper, springs for effecting movement of said means in one direction, and film controlled means for retaining the clapper

actuating means in the position where the springs are extended.

4. In combination with a motion picture reel having a hollow core, a signal gong mounted in said core, a rotary clapper member mounted for successive impacts with the gong when rotated, a slide mounted for movement radially of the reel and having a folding tongue for insertion between adjacent convolutions of a film found thereon, operative connections between the slide and the clapper, and tension springs for moving the slide radially inward.

5. In combination with a motion picture reel having a hollow core, a signal gong mounted within the core, a rotary clapper bar having terminal pivotally mounted pawls for successive impact with the gong when the bar is rotated, a slide mounted for movement radially of the reel, a rack bar having operative connection with said slide, speed multiplying gearing between said rack bar and said gripper bar, springs for effecting radial inward movement of the slide, and a tongue having a hinge connection with the slide and adapted for insertion between adjacent convolutions of film to retain the slide in a position where said springs are extended.

6. In combination with a motion picture reel having a hollow core, a signal gong mounted in said core, means for effecting a continuous sounding of the gong, said means including a slide movable radially of the reel and a guide in which said slide is mounted, and a tongue having a hinge connection with said slide and adapted for insertion between adjacent convolutions of film.

7. In combination with a motion picture reel having a hollow core, a signal gong mounted in said core, means for effecting a continuous sounding of the gong, said means including a slide movable radially of the reel and a guide in which said slide is mounted, a tongue having a hinge connection with said slide and adapted for insertion between adjacent convolutions of film, and a spring bearing laterally on the slide and adapted for engagement in lateral bearing upon the tongue upon radial inward movement of the slide.

In testimony whereof he affixes his signature.

JAMES H. STANFIELD. 120
